US00D604850S

(12) **United States Design Patent**
Lewis et al.

(10) **Patent No.:** **US D604,850 S**
(45) **Date of Patent:** **** Nov. 24, 2009**

(54) **ORTHOPEDIC BONE BLOCK ASSEMBLY**

(75) Inventors: **Wesley I. Lewis**, Archer, FL (US); **John R. Bianchi**, Gainesville, FL (US); **Joe Kutsavage**, High Springs, FL (US); **Arunas A. Zhukauskas**, Gainesville, FL (US)

5,067,962 A 11/1991 Campbell et al.
5,092,887 A 3/1992 Gendler
5,383,878 A 1/1995 Roger et al.
5,425,767 A 6/1995 Steininger et al.
5,443,509 A 8/1995 Boucher et al.
5,766,252 A 6/1998 Henry et al.

(57) **CLAIM**

The ornamental design for an orthopedic bone block assembly, as shown and described.

DESCRIPTION

FIG. 1 is a perspective view of an orthopedic bone block assembly showing our new design;

FIG. 2 is a front elevation thereof;

FIG. 3 is a back elevation thereof;

FIG. 4 is a left side elevation thereof;

FIG. 5 is a right side elevation thereof;

FIG. 6 is a top plan view thereof; and,

FIG. 7 is a bottom plan view thereof.

The broken lines in the drawings are included for the purpose of illustrating environmental structure and form no part of the claimed design.
